(57) **CLAIM**

The ornamental design for set of top and bottom inserts for securing cigars and liquids, as shown and described.

DESCRIPTION

FIG. 1 is a top perspective view of set of top and bottom inserts for securing cigars and liquids showing my new design;

FIG. 2 is a top plan view of the top insert thereof;
FIG. 3 is a bottom plan view of the top insert thereof;
FIG. 4 is an end elevation view of the top insert thereof, and the opposite end elevation view of the top insert is identical;
FIG. 5 is a side elevation view of the top insert thereof, and the opposite side elevation view of the top insert is identical;
FIG. 6 is a top plan view of the bottom insert thereof;
FIG. 7 is a bottom plan view of the bottom insert thereof;
FIG. 8 is an end elevation view of the bottom insert thereof, and the opposite end elevation view of the bottom insert is identical; and,

FIG. 9 is a side elevation view of the bottom insert thereof, and the opposite side elevation view of the bottom insert is identical.

The broken lines in FIG. 1 showing a case are for the purpose of illustrating the environmental structure and form no part of the claimed design. The broken lines in the corners of the top lid of the case reflect that the corners of the top lid of the case obscure portions of the top insert that are partially recessed into the top lid of the case.
